DESIGN FOR A MUSICAL CHIME

Evan G. Evans, Cincinnati, Ohio, assignor to Nu-tone Chimes Inc., New York, N. Y., a corporation of New York

Application October 27, 1938, Serial No. 80,713

Term of patent 7 years

To all whom it may concern:

Be it known that I, Evan G. Evans, a citizen of the United States, residing at Cincinnati, in the county of Hamilton and State of Ohio, have invented a new, original, and ornamental Design for a Musical Chime, of which the following is a specification, reference being had to the accompanying drawing, forming a part thereof.

I claim:

The ornamental design for a musical chime, as shown.

EVAN G. EVANS.
